UNITED STATES PATENT OFFICE.

ANE P. SCHAT, OF Utrecht, NETHERLANDS.

SELF-CONTAINED AUTOMATIC TACKLE.

Application filed February 3, 1921, Serial No. 442,033, and in the Netherlands December 20, 1919.
Renewed July 23, 1928.

My invention relates to hoisting and lowering devices, and will be described in this specification with special reference to its use with lifeboats. The Netherlands application 5 for patent of this invention, was filed Dec. 20, 1919, No. 13,623.

Lowering a lifeboat is, as a rule, effected by men standing on deck of the ship, and when a heavy boat is to be lowered with the ordinary pulley blocks, each fall has to be carefully held and paid out by two men, thus requiring four men to handle the falls; while a fifth man is required for watching the descent of the boat and for transmitting to the men on 10 deck who are paying out the falls the orders received from the man who is in command on the descending boat. The five men on deck have to remain behind till the boat is safely launched, and then they may slide down into 15 it on ropes specially prepared for that purpose.

With smaller boats fewer men are required to remain on deck, and modern appliances aim to still further reduce this number, but in 20 doing so the danger to those in the boats is generally increased.

When the boat is lowered by two independent falls, one fall is often paid out faster than the other, which throws the keel of the boat 25 out of horizontal position.

In an attempt to overcome these and other difficulties, means have been provided whereby the falls may be paid out by men standing in the lifeboat itself, but this requires the 30 taking up of the coiled up falls into the boat where they are liable to get badly tangled in a way to seriously interfere with the lowering operation, to say nothing of being a source of annoyance and danger to the occupants of 35 the boat; and finally when the boat is released from the blocks and launched, the tangled falls must be thrown overboard, which may again cause serious difficulty.

If the falls are arranged to be wound on a 40 drum on deck, a separate rope must be employed to operate the drum, and this rope is liable to get entangled and render the operation of the drum impossible.

The object of the present invention is to 45 avoid the above disadvantages and to provide means whereby the lifeboat may be lowered by persons standing in the boat—by one person alone if need be—without the falls being taken into the boat, and without the need 50 of an additional rope, the entire operation

only requiring the use of the ordinary ropes rove through the pulley blocks from which the boat is suspended.

Another object is to provide means located in or adjacent to the lower pulley block, for 55 performing the above operation.

More specific objects are to provide means for utilizing the weight of the boat to automatically brake and release the pulleys, and also when desired, the rope which passes therethrough; and further means for regulating 60 said automatic braking and releasing means, or for controlling the same independently of the weight of the boat, all being under the perfect control of one man in the boat.

Still another object is to utilize the differences of tension in different parts of the tackle rope for automatically braking and releasing the different parts as above referred to.

Another object is to provide a tackle in 70 which the hauling part of the tackle is completely relieved of all strain, so that the load, when desired, may remain poised at any height entirely under the action of its own weight, without the free end of the hauling 75 cable being held at all by the hand of the operator or otherwise.

Another important object is to provide means on deck (preferably a drum) for receiving and paying out the tackle rope, said 80 drum being provided with loaded braking mechanism operated by a spring or weight, and adapted to take up the major portion 85 of the strain imposed upon the rope by the weight of the load, thereby leaving only a slight braking duty to be performed by the 90 braking mechanism of the tackle.

A still further object is to provide means in addition to said last named means for further utilizing the difference in the tension in 95 different parts of the tackle rope for automatically controlling the brake of said winch drum on deck instead of controlling it by a spring or weight as just above stated.

Other objects will appear in the subjoined 100 description.

An important feature of the invention consists in providing the lower block of the tackle with a lever having a long and a short arm, the short arm carrying a brake adapted 105 to be moved into and out of frictional engagement with one or more pulleys of the block, and the long arm being arranged to be pressed in opposite directions by the difference in tension in the standing and haul- 110

ing part of the rope, according to whether the load is being raised or lowered or held poised on the tackle, the arrangement being such that when the boat is being elevated 5 the brake is automatically moved out of engagement with the pulley, and when it is being lowered, it is automatically pressed into engagement therewith, and if desired, with a force sufficient to hold the boat poised;

10 said longer arm of the lever being also provided with an extension for manually easing up the automatic braking pressure sufficiently to permit the boat to descend, or for increasing said pressure, if need requires.

15 In carrying out the present invention, I have provided automatic means whereby one or more pulleys of one of the blocks—preferably the lower block—are prevented from revolving during the veering operation, but all 20 the pulleys of the block have freedom of rotation during the hoisting operation.

The invention consists in certain novel features of construction and arrangement of parts as will be hereinafter described and 25 claimed, reference being had to the accompanying drawings in which;—

Fig. 1 is a front view of a tackle embodying my improvements, with the hooks omitted from the blocks.

30 Fig. 2 is a side view of the same; and,

Fig. 3 is a view showing means on deck for automatically controlling the hauling end of the tackle rope; and

35 Fig. 4 is a detail view showing a method of adjustably connecting the cross rods with the thrust bars.

In the construction shown, the fixed block 1 of the tackle and the running block 2 are each provided with three pulleys, 3, 4, 5, and 40 6, 7, 8, respectively. The load cable is secured at one end of the casing of the fixed block 1, and then passed successively over pulleys 8, 5, 6, 3, 7, and 4. The side plates 9 and 10 of the running blocks 2 are each 45 provided with two horizontal slots 11 and 12 in alignment with each other for receiving and guiding the ends of cross rods 13 and 14 coupled by rigid members 15 and 16 provided on the outside of the plates 9 and 10, so that 50 the ends of said slots serve as abutments for limiting the horizontal movement of the rods 13 and 14. The rod 13 carries an anti-friction roller 17 in permanent engagement with the fixed part 18 of the load cable which part 55 is secured at its upper end to the cross rod 9* of the upper pulley block, and the rod 14 carries an anti-friction roller 19 in permanent engagement with the hauling part 20 of said cable between the pulleys 7 and 4.

60 Positively mounted on the rod 14 is the upper end of a lever 21 keyed on a pin 22 which is rotatably mounted in bearings in the plates 9 and 10, and keyed on said pin are two brake shoes 23 and 24 having beveled 65 edges and each adapted to engage corre-

spondingly beveled edges of the adjacent pulleys 6, 7, and 7, 8, respectively.

The length of the rigid members 15, 16, is such that the pressure exerted by the rollers 17, 19, on the parts 18 and 20, respectively, of the cable, produce in said parts bights 25, 26, which, owing to the weight of the load, have a permanent tendency to straighten themselves.

It is well known that when the load is 75 hoisted, the tension in the hauling part considerably exceeds that in the fixed part of the cable, so that the tension of part 20 exceeds that of part 18, whereby the rods 13, 14, in Fig. 1, are moved to the left. This causes the lever 21 to move inwardly through a certain angular distance, whereby the brake is released, and the pulleys 6, 7, 8, are permitted to freely revolve about their shaft. When the load cable is paid out, however, the tension in the fixed part exceeds that in the yielding or hauling part, so that the rods 13, 14, are moved to the right, and the brake shoes are pressed against the beveled edges of the pulleys 6, 7, 8, whereby the turning movement of said pulleys is counteracted. As soon as the brake is applied, the difference in the tensions in the fixed part 18 and the hauling part 20 is still further increased, and consequently 85 the braking power is also increased.

Keyed on pin 22 is a third brake shoe 27 adapted to be pressed against the load cable on pulley 7, simultaneously with the application of brake shoes 23, 24, on the pulleys 6 and 8, whereby the tendency of the cable to slip on pulley 7 is counteracted.

The lever 21 has an extended portion 28 provided with a handle 29, by means of which the pressure brought about by the brake shoes 23, 24, and 27, on the pulleys 6, 7, 8, and on the part of the cable led around pulley 7, respectively, may be manually controlled.

As shown in the drawings, especially in Fig. 4, the ends of the rods 13, 14, which project beyond the slots 11, 12, are reduced and threaded, shoulders being formed on said rods at the points where they are reduced. Said threaded ends are provided with nuts $\times$ which serve to hold the bars 15, 16 in rigid engagement with said shoulders in adjusted positions in the slots 11*, 12* of the thrust bars 15, 16 (Figs. 3 and 4), whereby to provide means for increasing or decreasing the bights 25, 26, in order to vary the braking power of said bights.

From the construction shown and described, it will be seen that when the pulleys 6, 7, 8, are braked to a stand-still by the weight of the load, they will then act as bollards if the tackle rope be paid out. This distributes 125 the braking friction over a large surface, thereby making it easy on the rope.

It has been previously stated that it is one of the objects of the invention to provide a tackle that will stand poised at any height 130

by the weight imposed upon it without the necessity of holding the free end of the hauling rope; or, let us say that it is a self-contained tackle, in that respect. It is well known for instance that when using a winch drum for hoisting or lowering a load, it is always necessary to secure the hauling part of the rope on the drum, irrespective of the number of turns of rope around the drum, as otherwise the load would slip as soon as the load is freely suspended from it. The same is true of ordinary tackles and pulley blocks, the pulleys of which are held against rotation during the lowering of the load. If in such constructions the hauling part did not have at least some tension in it, the coils on the drum would loosen beginning at the hauling end, and the load would simply fall by gravity. In the present invention the hauling part of the load cable is gripped by the brake shoe 27 preferably under the influence of the tensions prevailing in the cable when the same is loaded.

With my present construction, the means for holding the pulleys against rotation and for locking the hauling part of the load cable are automatically rendered inoperative when the load is hoisted.

From my invention as described, it will be seen that the braking mechanism connected with the lower block of the tackle, makes it easy to control the descent of a boat by persons in the boat, since the braking of the pulleys is automatic, and always in direct proportion to the weight of the load. The parts of the device may be so adjusted to each other that the automatic braking effect of the load is just sufficient to hold the boat poised, or normally braked to a stand-still, in which case the boat is lowered by slightly easing up the pressure on the brake shoes, through a proper manipulation of the hand lever 28. Again, the parts may be so adjusted that the boat would normally descend, in which case its descent would be suitably retarded by manually operating said lever 28.

The principal advantage of my arrangement is that the lowering of the boat may be effected by persons in the boat without the necessity of taking the coiled up fall along in the boat.

Having now particularly described my said invention, what I claim as new and desire to protect by Letters Patent is:—

1. In a tackle for handling lifeboats, a running block with opposing side plates and a plurality of pulleys, all of said pulleys being mounted between said plates and in alinement with each other; and means for utilizing the weight of the boat to simultaneously brake the pulleys of said block and pay out the hauling end of the tackle rope under control.

2. In a tackle for handling lifeboats, a running block with opposing side plates and

a plurality of pulleys, all of said pulleys being mounted between said plates and in alinement with each other; brakes for said block; means for utilizing the weight imposed upon the tackle to apply the brakes to the pulleys of said block as the load is lowered, and to force the brakes out of engagement with the pulleys as the load is elevated.

3. In a tackle for handling lifeboats, the combination with one of the tackle blocks of a running block with opposing side plates and a plurality of pulleys, all of said pulleys being mounted between said plates and in alinement with each other; brakes for said block means for utilizing the weight imposed upon the tackle to simultaneously apply the brakes to the pulleys of said block and pay out the hauling part of the tackle rope under control as the boat is lowered, and to positively release the brakes and the hauling part of the tackle rope as the boat is elevated.

4. A tackle having a running block comprising opposing side plates and a plurality of pulleys, all of said pulleys being mounted between said plates and in alinement with each other; means operable by the weight of the load, as the load is lowered, for braking the pulleys of said block, and for paying out under control the hauling part of the tackle rope.

5. A tackle having a running block comprising opposing side plates and a plurality of pulleys, all of said pulleys being mounted between said plates and in alinement with each other; means, as the load is lowered, for braking the pulleys of said block and for paying out under control the hauling part of the tackle rope, and also for releasing said brakes and hauling end of the rope, as the load is elevated.

6. A tackle having a running block comprising opposing side plates; a transverse axle mounted on said plates; alined pulleys rotatably mounted on said axle between said plates, with the tackle rope led around said pulleys; braking means for the tackle rope; and automatic means operable in one direction by the weight of the load to exert a force proportionate to the weight of the load for applying said braking means directly to the alined pulleys as the load descends, and for positively releasing said braking means, as the load is elevated.

7. In tackles for lowering lifeboats, a block having alined pulleys; brakes for engaging said pulleys, one of said pulleys having the hauling part of the tackle rope led around the same; another brake adapted to press the hauling part of the tackle rope against said pulley around which it is led, to hold the hauling part of the tackle rope against loosening on the pulley blocks; and means for utilizing the weight of the burden imposed upon the tackle to operate all of said brakes.

8. In tackles for lowering lifeboats, a block having alined pulleys; brakes for engaging said pulleys, one of said pulleys having the hauling part of the tackle rope led around the same; another brake adapted to press the hauling part of the tackle rope against said pulley around which it is led, to hold the hauling part of the tackle rope against loosening on the pulley blocks; means for utilizing the weight of the burden imposed upon the tackle to operate all of said brakes; and additional means for controlling said brakes independently of the burden imposed upon the tackle, and also in cooperation therewith.

9. In a device of the character described, a tackle block comprising opposing side plates; an axle mounted in said plates; alined pulleys rotatably mounted on said axle between said plates, with the tackle rope led around said pulleys; and braking means for the tackle automatically operated by the weight of the load and arranged to apply the brakes directly to said alined pulleys as the load descends and when the load is poised; and manual means for applying and releasing the brakes independently of the weight of the load, and also in conjunction therewith.

10. In tackles for handling lifeboats, a block having alined pulleys; brakes for engaging said pulleys, one of said braked pulleys having the hauling part of the tackle rope led around the same; another brake movable in unison with said first named brakes and adapted to press said hauling part of the tackle rope against the pulley around which it is led, to hold the hauling part of the tackle rope against loosening on the pulley blocks; means for utilizing the weight of the burden imposed upon the tackle, to simultaneously apply all of said brakes as the load is lowered and when it is poised and to force them into inoperative position when the load is elevated; and additional means for manually manipulating said brakes.

11. In a tackle for handling lifeboats, a block having alined pulleys with inclined peripheral margins on their opposing faces, one of said pulleys having the hauling part of the tackle rope led around the same; brakes having shoes with inclined bearing surfaces adapted to fit between adjacent pulleys in engagement with said inclined peripheral faces; another brake movable in unison with said first named brakes and having a shoe for entering the annular groove of the pulley around which the hauling part of the tackle rope is led, said shoe being sufficiently narrow to enter said groove without contacting with the sides thereof, and having a braking surface adapted to press the hauling part of the tackle rope in said groove, to yieldingly hold the same against loosening on the pulley blocks and to pay out the same under control as the

load is lowered; means for utilizing the weight of the burden imposed upon the tackle to apply all of said brakes as the load is lowered and when it is poised, and to force them into inoperative position when the load is elevated; and a lever connected with said brakes for manually controlling the same independently of the burden of the tackle and also in cooperation therewith.

12. In a tackle for handling lifeboats, a block having alined pulleys with the hauling part of the tackle rope led around one of said pulleys; brakes for said pulleys; another brake adapted to press the hauling part of the tackle rope against said pulley around which it is led, to hold the hauling part of the tackle rope against loosening on the pulleys and to pay out said part of the tackle rope under control as the boat is lowered; a bar for engaging the standing and hauling parts of the tackle rope to form bights therein by which bights said bar is simultaneously pressed in opposite directions, whereby to move said bar in whichever direction the resultant pressure is the greatest; all of said brakes having their shoes rigidly mounted on a common axle; an operating lever rigidly connected to said axle for operating said brake shoes, said lever being also operatively connected to said bight-bar, whereby when the resultant pressure moves the bar in one direction the brakes are all simultaneously moved into operative position, and when the resultant pressure moves the bar in the opposite direction the brakes are all moved into inoperative position.

13. In a tackle for handling lifeboats, a block having alined pulleys, with the hauling part of the tackle rope led around one of said pulleys; brakes for said pulleys; another brake movable simultaneously with said pulley brakes and adapted to press the hauling part of the tackle rope against said pulley around which it is led, to hold the hauling part of the tackle rope against loosening on the pulley blocks, and to pay out said part of the tackle rope under control as the boat is lowered; mechanism between the standing and hauling parts of the tackle rope simultaneously pressed in opposite directions by the different tensions prevailing in said parts in the varying conditions under which the tackle is used; and connections between said mechanism and the brakes for utilizing the differential of said tensions to operate the brakes; whereby when the differential is in one direction, the brakes are moved into operative position, and when it is in the opposite direction they are moved into inoperative position.

14. In a tackle for handling lifeboats, a block having a pulley with the hauling part of the tackle rope led around it; a brake adapted to press said hauling part of the tackle rope against said pulley around which

- it is led to hold said hauling part against loosening on the tackle pulleys, and to pay out said part of the tackle rope under control as the boat is lowered; mechanism between 5 the standing and hauling parts of the tackle rope simultaneously pressed in opposite directions by the different tensions prevailing in said parts in the varying conditions under which the tackle is used; and connections between said mechanism and the brake for utilizing the differential of said tensions to operate the brake; whereby when the differential is in one direction the brakes are moved into operative position, and when it 10 is in the other direction the brakes are moved into inoperative position.
15. In a tackle for lowering a lifeboat from within the same, the combination with the running block of the tackle, of brakes for its pulleys; and means for utilizing the difference in tension in the standing and hauling parts of the tackle rope to operate said brakes.
16. In a tackle for lowering a lifeboat 20 from within the same, the combination with the running block of the tackle, of brakes for its pulleys; and means for utilizing the difference in tension between the standing and hauling parts of the tackle rope to move 25 the brakes into operative relation to the pulleys when the load is lowered, and to force them away from the pulleys when the load is elevated.
17. In a tackle for lowering a lifeboat 30 from within the same, the combination with the running block of the tackle, of brakes for its pulleys; and means for utilizing the tension in the standing part of the tackle rope to press the brakes into operative engagement with the pulleys, and in the hauling part to press the brakes away from the pulleys.
18. In a tackle for lowering a lifeboat 35 from within the same, said tackle having pulleys and brakes therefor, the combination with the running block of the tackle, of means for utilizing the difference in tension between the standing and hauling parts of the tackle rope to automatically move the brakes 40 into engagement with the pulleys when the load is lowered and away from the pulleys when the load is hoisted up.
19. In a tackle for lowering a lifeboat 45 from within the boat, the combination with the running block of the tackle, of brakes for its pulleys, and mechanism for positively applying and releasing the brakes; bights in the standing and hauling parts of the tackle rope; operative connections between said 50 bights and the braking mechanism, said connections being pressed in opposite directions by said bights to apply or release the brakes, according to the direction in which the tackle is operated.
60. In a tackle for lowering a lifeboat from within the boat, a running block having aligned pulleys rotatable on an axis held in fixed position relative to said block; a standing block; and means for utilizing the difference of tension in the standing and hauling 70 parts of the tackle rope to pay out, from the running block to the standing block, the hauling part of said rope under control as the load is lowered.
21. In a tackle for lowering a lifeboat 75 from within the boat, a running block having aligned pulleys rotatable on an axis held in fixed position relatively to said block; a standing block; and means for utilizing the difference in tension between the standing and hauling parts of the tackle rope to yieldingly hold and pay out, from the running block to the standing block, said hauling part of the rope under control as the load is lowered, and to positively release the same as the 80 load is elevated.
22. A tackle having its running block provided with a plurality of pulleys all in fixed axial alignment with each other; braking means operable by the weight of the load for applying the brakes to the aligned pulleys as the load descends; and further braking means also operable by the weight of the load for yieldingly pressing the hauling end of the 85 tackle rope as the load descends.
23. A tackle having a running block and a standing block, with its running block provided with a plurality of pulleys all in fixed axial alignment with each other, said tackle having one rope only with the hauling part 90 of the same extending from the standing block to the running block; braking means operable by the weight of the load for applying the brakes to the aligned pulleys; and additional braking means also operable by the 95 weight of the load for braking the hauling end of the rope proportionate to the weight of the load.
24. A tackle having pulleys and braking mechanism, comprising brake shoes for engaging the pulleys; a lever for operating said shoes; bights in the tackle rope for engaging said operating lever, to move the same back and forth to apply the brakes and to release the same according to the direction of said movement, one of said bights being in the standing part of the tackle rope and the other in the hauling part; and adjustable means for increasing or decreasing the bights to vary the automatic braking power of the tackle. 100
25. A tackle having pulleys and braking mechanism, comprising brake shoes for engaging the pulleys; a lever for operating said shoes; bights in the tackle rope for engaging said operating lever, to move the same back and forth to apply the brakes and to release the same according to the direction of said movement, one of said bights being in the standing part of the tackle rope and the other in the hauling part; adjustable means for 105
- 110
- 115
- 120
- 125
- 130

increasing or decreasing the bights to vary the automatic braking power of the tackle; and means for manually controlling said braking mechanism.

5 26. In a tackle, a running block having opposing side plates and a plurality of pulleys all mounted between said side plates in alignment with each other; mechanism carried by the tackle for yieldingly gripping the hauling part of the tackle rope as the load is lowered; said mechanism being also adapted to automatically release said grip as the load is elevated.

15 27. In a tackle, a running block having opposing side plates and a plurality of pulleys all mounted between said side plates in alignment with each other; and mechanism carried by the block for utilizing the differential of tension between the standing and hauling 20 parts of the tackle rope to pay out under control the hauling part of the tackle rope.

25 28. In a device of the character described, means for handling a lifeboat from within the boat, comprising a tackle for raising and lowering the boat, said tackle having a running block supported from the deck of the ship; a drum on the deck for the hauling part of the tackle; and means associated with the running block of the tackle for 30 controlling the rotation of the drum.

35 29. In a device of the character described, means for lowering a lifeboat from within the boat, comprising a tackle for supporting the boat from ship deck; a drum on the deck with the hauling part of the tackle rope wound around said drum; braking mechanism for the drum; and means associated with the running block of the tackle for controlling said braking mechanism, whereby to control the paying out of 40 the tackle by the drum.

45 30. In a device of the character described, means suspended from ship deck for lowering a lifeboat from within the boat, comprising a tackle for each end of the boat, each tackle having an upper and lower block; a drum on the deck with the hauling parts of the two tackle ropes both wound around said drum; braking mechanism for the 50 drum responsive to variations in the pull thereupon by the tackle ropes; and means associated with the lower block of one of

the tackles for varying the tension on the hauling end of said tackle; whereby to control the rotation of the drum, and through it 55 the lowering of the boat.

31. In a device of the character described, means for lowering a lifeboat from within the boat, comprising a tackle for supporting the boat from the deck of the ship, said 60 tackle having upper and lower blocks; a drum on the deck for the hauling part of the tackle, said hauling part being coiled around the drum; and means associated with the lower block of the tackle for manually controlling the rotation of the drum.

32. In a device of the character described, means for lowering a lifeboat from within the boat, comprising a tackle for supporting the boat from the deck of the ship, said 70 tackle having a running block; a drum on the deck with the hauling part of the tackle rope wound around said drum; automatic braking mechanism for the drum; and means including a lever associated with the running 75 block of the tackle for controlling said braking mechanism, whereby to control the paying out of the boat fall by the drum, as the boat descends.

33. In a device of the character described, 80 means for lowering a lifeboat from within the boat, comprising a tackle for supporting the boat from the deck of the ship, said tackle having upper and lower blocks; a drum on the deck with the hauling part of the tackle 85 rope wound around the same; and a lever associated with the lower block of the tackle for manually controlling the rotation of the drum.

34. In a device of the character described, 90 means for lowering a lifeboat from within the boat, comprising a tackle for supporting the boat from the deck of the ship; a drum on the deck with the hauling part of the tackle rope wound around the same; means 95 for braking the drum proportionately to the strain imposed upon the hauling part of the tackle rope; and mechanism, including a lever, for varying the tension in said hauling part of the rope, whereby to regulate the 100 paying out of the tackle by the drum.

In testimony whereof I affix my signature.

ANE P. SCHAT.
